Primary Examiner — Rosemary K Tarcza*Assistant Examiner* — James Thorn, Sr.(74) *Attorney, Agent, or Firm* — Taylor J. Ross(57) **CLAIM**

The ornamental design for a juicer, as shown and described.

DESCRIPTION

FIG. 1 is a top, front and left side perspective view of a juicer in the closed position showing my new design;

FIG. 2 is a bottom, rear and left side perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view, the right side being a mirror image thereof;

FIG. 8 is a top, front and left side perspective view of the juicer in the open position showing our new design;

FIG. 9 is a bottom, front and right side perspective view of the juicer in the open position;

FIG. 10 is a top plan view of the juicer in the open position;

FIG. 11 is a bottom plan view thereof in the open position;

FIG. 12 is a front elevation view thereof;

FIG. 13 is a rear elevation view thereof; and,

FIG. 14 is a left side elevation view, the right side being a mirror image thereof.
